UNITED STATES PATENT OFFICE.

EDWARD WILLIAMS, OF MONESSEN, PENNSYLVANIA, ASSIGNOR TO WILLIAMS WELDING AND MANUFACTURING COMPANY, OF CHARLEROI, PENNSYLVANIA, A CORPORATION OF PENNSYLVANIA.

PORT COOLER FOR OPEN-HEARTH FURNACES.

Application filed December 1, 1926. Serial No. 151,975.

This invention relates to metallurgical furnaces and more especially to open hearth furnaces, the object of the invention being to provide means whereby a cooling medium 5 may be supplied about the port through which the heated currents pass to the hearth so that the disintegration of the brick-work of the furnace will be resisted and practically overcome. Another object of the invention 10 is to provide a device for applying the cooling medium which will be simple in construction and may be easily applied at low cost to the furnace. The invention is illustrated in the accompanying drawings 15 and will be hereinafter fully described, the novel features being particularly pointed out in the appended claim.

In the drawings:

Figure 1 is a longitudinal section of a portion of an open hearth furnace having the invention embodied therein;

Fig. 2 is a transverse section on the line 2—2 of Fig. 1;

Fig. 3 is a detail longitudinal section 25 through the cooling apparatus;

Fig. 4 is a section on the line 4—4 of Fig. 4, and

Fig. 5 is an end view of the structure illustrated in Fig. 3.

The furnace, indicated generally by the reference numeral 1, may be of any approved construction and embodies a passage or flue 2 through which the heat is conducted to the hearth chamber. The cooling device constituting my present invention is applied to the furnace immediately about the port 3 through which the heated currents enter the hearth chamber and includes tanks 4 and 5 which are set in the walls of the furnace and 35 extend transversely of the furnace in alignment to terminate at the sides of the port or arch. The inner opposed ends of the tanks are connected at the bottoms thereof by a plurality of pipes 6 whereby water delivered into one tank will flow into the other tank and fill the said pipes so that a body of water will be established at each side of the arch and will rise to a common level in both tanks. The inner opposed ends of the 45 tanks are also connected at their tops by a plurality of arched pipes or tubes 7 which also establish free communication between the tanks. Both tanks are provided at their outer ends with manholes, indicated at 8,

whereby access may be had to the tanks when necessary to clean or repair the same and they are also provided at their outer ends with projecting flanges or anchoring plates 9 through which any approved form of bolts or other anchoring elements may be inserted into the corresponding adjacent portions of the furnace walls or the reinforcing frame of the furnace, rigidity in the location of the tanks being thereby assured. An inlet or supply water pipe 10 enters the outer end of the tank 5 and extends through the said tank over the bottom thereof to a point near the tubes 6 where it enters a coupling 11 whereby a plurality of delivery pipes or nozzles 12 may be connected to the supply pipe. One of these nozzles or delivery pipes will be provided for each one of the tubes 6 and the several nozzles or delivery pipes enter the respective tubes and terminate at the center of the same so that the water will be delivered most advantageously to secure an even distribution of the same within the two tanks and provide for an even temperature throughout the structure. A pipe 13, similar to the pipe 10, is provided at the top 50 of the tank 5 and this pipe 13 is also connected to a coupling 14 from which arched nozzles 15 extend into the respective arched tubes 7, as clearly shown in Fig. 3. The outer end of the pipe 13 may be led to a sewer or other point of discharge, and said pipe with its nozzles 15 constitute an overflow permitting the escape of the hot water so that a constant circulation of water may be effected, the hot water passing out and 55 cold water entering to take the place of the hot water which is carried off. To control the flow or possibly cut it off altogether, the inlet pipe may be provided with an ordinary cut-off valve (not shown) in any convenient 60 point of its length.

The tanks are constructed of metal and all the joints are welded so that they will effectually withstand the intense heat in the furnace walls. The several pipes shown and described are arranged within the tanks before the tops thereof are placed in position and the joints of the pipes are all welded or otherwise rendered leak-proof. After the several pipes are in place, the tops of the tanks are placed in position and are welded to the side and end walls of the tanks so that, barring accident, there will be no leak- 65 70 75 80 85 90 95 100 105

age of the water to cause damage to any part of the furnace. The device is exceedingly simple and may be readily applied to any furnace at a low cost.

5 Having thus described the invention, I claim:

An apparatus for the purpose set forth comprising a pair of aligned tanks adapted to be embedded in the walls of a furnace at opposite sides of a heat passage therethrough, a plurality of tubes connecting the inner ends of the tanks at the bottom there-

of, a plurality of tubes connecting the inner ends of the tanks at the top thereof, a cold water supply pipe entering one of the tanks 15 at the bottom of the same and terminating in delivery nozzles each located in one of the first-mentioned tubes, and a hot water drain pipe extending from the tank at the top thereof and terminating at its inner end in a plurality of nozzles each disposed in one of the second-mentioned tubes.

In testimony whereof I affix my signature.
EDWARD WILLIAMS. [L. S.]
